UNITED STATES PATENT OFFICE.

CHARLES D. CLARK, OF CHICAGO, ILLINOIS, ASSIGNOR TO THE WILLIAM DEERING & COMPANY, OF SAME PLACE.

MOLDING-MACHINE.

SPECIFICATION forming part of Letters Patent No. 419,639, dated January 21, 1890.

Application filed September 29, 1888. Serial No. 286,742. (No model.)

To all whom it may concern.

Be it known that I, CHARLES D. CLARK, a citizen of the United States, residing at Chicago, county of Cook, and State of Illinois, have invented certain new and useful Improvements for Molding-Machines, which are fully set forth in the following specification, reference being had to the accompanying drawings, forming a part thereof.

10 In the drawings, Figure 1 is a plan of my molding-machine with the patterns for a common hand-wheel secured therein, a piece of the follow-board being broken away about one pattern. Fig. 2 is a longitudinal section 15 through the same, showing the molding-sand in position about the pattern in one half of the machine, and showing the sand mold withdrawn from the pattern and bearing the reverse impress of it in the other half of the 20 machine. Fig. 3 is a side elevation of the parts in the position shown in Fig. 2. Fig. 4 is a section at the line 4 4 on Fig. 1.

A is the frame, which is an oblong parallelogram comprising the vertical sides A' and the 25 ends A², and supported by four standards D D D, secured to it at the four corners. The ends A² have the outwardly-extending flanges A²⁰. The side bars A' are joined by the transverse bars A¹⁰ A¹⁰, which are joined at the top 30 by the horizontal web A¹¹, and the said side bars are further connected by the transverse flat bars A¹² A¹² A¹² A¹². The ends A² and the transverse bars A¹⁰ guide the follow-boards. The lower edges of the side board A' are cut away 35 at a' a' a' a', and between said cut-away portions are turned outward and up to form the channeled slide-bearing A¹³, in which devices for lifting the follow-board obtain bearing, as hereinafter particularly described.

40 B B are follow-boards formed with the downwardly-extending flanges B' B', which fit between and are guided by the ends A² and the vertical cross-bars A¹⁰, respectively. The follow-boards extend out over the upper edges 45 of the side bars A' A' and have downwardly-extending flanges B² B² outside said side bars, which flanges are cut away, leaving the wedge-shaped cam portions B²⁰ B²⁰, having the slanting under edges b²⁰, as seen in Fig. 3. Said 50 flanges directly overhang the channeled slide-

bearings A¹³ of the frame A, and between them and said bearings, respectively, is located the slide C, comprising the two wedge-shaped cams C' C' correlative to the wedge-shaped cam portions B²⁰ B²⁰ of the flanges B². These cams C' 55 are connected by the cross-bars C² C², which extend underneath the frame A from side to side, crossing the under edge of the side bars A' in the cut-away portions a', and to the under side of said cross-bars midway in the width 60 of the frame A there is secured the rack C³.

In the two standards D D, at each end of the machine, there is journaled a shaft E, to which there is secured a handle E' and a segment-gear E², which meshes with the rack C³, 65 the handle serving to rock the shaft and segment-gear and cause the latter to actuate the rack and to carry with it longitudinally the slides C'. To the upper side of said follow-boards B there is secured the flask F, for retaining the molding-sand and mold when completed. The flasks F have the horizontal flanges F', which lap the flanges A²⁰ and the web A¹¹ of the frame A. One of the flasks has the dowel-pins f' secured in its flange F', and 75 the other has in a corresponding position holes adapted to admit similar dowel-pins f', which are secured in the web A¹¹ and flange A²⁰ of the frame. These pins are for the familiar purpose of guiding the two flasks together 80 when they are placed face to face. They also serve to fix the exact position of the flasks on the follow-boards, so that when two flasks are united the two parts of the mold formed in them respectively are accurately matched together. 85

The operation of this mechanism will be obvious upon inspection; but for further certainty it will be described. The patterns, which are made in mated pairs, each of which is 90 adapted to produce one half of a mold for casting the desired article, are secured to the cross-bars A¹² of the frame, as shown in Fig. 2. Preferably the machine is made double, as shown, so that in each half there may be 95 formed a mold of the two parts of the article to be cast, said parts being arranged in opposite order in the two portions of the machine, so that the double half-molds thus made, being applied to each other face to face, form 100

two complete molds of the desired article. The apparatus being first in the position shown in the left half of Fig. 2, the follow-board being at its lowest position and the flask resting upon the frame A, patterns being secured in position and the sand tamped in above them, the operator, by means of the handle E', rocking the shaft E and the segment-gear E², causes the slides C² to move longitudinally in their bearings A¹³, and their upper sloping edges C', engaging the lower sloping edges B²⁰ of the flanges B², force the follow-boards and flasks directly upward, carrying the mold away from the pattern. The mold being thus completely freed of the pattern and the corresponding half being at the same time in a similar manner formed in the other half of the machine, the two half-molds are ready to be applied face to face and made ready for the metal.

20 I claim—

1. In a molding-machine, in combination with the frame A, having the patterns secured thereto, and the horizontal slide-bearings A¹³, the follow-board B, having the cams B²⁰ overhanging said slide-bearings, respectively, and

the slide-cams C' interposed between said slide-bearings and said cams B²⁰ on the follow-boards, substantially as and for the purpose set forth.

2. In a molding-machine, in combination with the frame having the side bars A', and supports for securing the pattern thereto and having the horizontal slide-bearings A¹³, the follow-boards having vertical guide-bearings on said frame and having the cams B²⁰ overhanging said guide-bearings A¹³, and the correlated sliding cams C' interposed between the cams B²⁰ and the slide-bearings, respectively, said correlated cams being rigidly connected, and means, substantially as described, for actuating them longitudinally with respect to said slide-bearings, substantially as set forth.

In testimony whereof I have set my hand in the presence of two witnesses, at Chicago, Illinois, this 24th day of September, A. D. 1888.

C. D. CLARK.
